UNITED STATES PATENT OFFICE.

BERNARD O. UMHAU, OF WASHINGTON, DISTRICT OF COLUMBIA.

LUBRICATOR FOR ELEVATOR-GUIDES.

996,168.

Specification of Letters Patent. Patented June 27, 1911.

Application filed February 21, 1911. Serial No. 610,101.

To all whom it may concern:

Be it known that I, BERNARD O. UMHAU, a citizen of the United States, residing at Washington, in the District of Columbia, 5 have invented a new and useful Lubricator for Elevator-Guides; and I do hereby declare the following to be a full, clear, and exact description of the invention, such as will enable others skilled in the art to which 10 it appertains to make and use the same.

This invention relates to a new and useful lubricator adapted to be carried by an elevator and provided with means for partially embracing the guide track of the ele- 15 vator, so as to lubricate the same.

The invention in its broadest scope aims as its primary object to provide a practical, simple and efficient lubricator having a frame, for the support of a globular oil cup 20 or receptacle and fabric feeding wicks leading from the cup and supported by an adjustable frame (consisting of two parts), for supplying the gravitating or compres- 25 sion members with oil or grease. These gravitating or compression members are designed to engage the faces of the guide rail or track of the elevator shaft. The object in providing the adjustable two-part frame is to increase or decrease the space between the 30 gravitating or compression members, so as to accommodate guide rails or tracks of different thicknesses.

A further object of the invention is to provide metallic means clamped in the fabric 35 wicks of the gravitating compression members, in order to engage the surfaces of the guide track or rail, thus obviating the possibility of the extremities of the wicks becoming quickly and considerably worn.

40 In the drawings, however, there is only disclosed one form of the invention, but, in practical fields, this form may require alterations, to which the applicant is entitled, provided the alterations are comprehended 45 by the appended claims.

The invention comprises further features and combinations of parts hereinafter set forth, shown in the drawings and claimed.

In the drawings:—Figure 1 is a view in 50 elevation, showing the application of the lubricator upon an elevator car, and constructed in accordance with the invention. Fig. 2 is a top plan view of the lubricator, showing the extreme top plate of the frame 55 thereof removed. Fig. 3 is a sectional view on line 3—3 of Fig. 2. Fig. 4 is a sectional

view on line 4—4 of Fig. 2. Fig. 5 is a detail perspective view of one of the members, for holding and suspending the wicks. Fig. 6 is an enlarged detail sectional view trans- 60 versely through one of the gravitating compression members. Fig. 7 is a view of one of the gravitating or compression members, showing the parts thereof disassembled. Fig. 8 is a sectional view on line 8—8 of 65 Fig. 3.

Referring to the drawings, 1 denotes the elevator car or cage, which is provided with an arm 2, while 3 designates the arms of the U-shaped member 4, which is secured by 70 bolts and nuts 5 to the frame 6 of the lubricator. The frame 6 consists of three plates 7, 8 and 9. The plates 7 and 8 are considerably spaced apart by the standards 10, through which the screw bolts 11 penetrate. 75 The plate 9, however, is arranged immediately above the plate 8, and held separated from the plate 8 by the nuts 12, which are threaded upon the screw bolts 11. The plate 9 is secured in place by the nuts 13 which 80 also are threaded to the screw bolts. Remov- ably arranged between the plates 7 and 8 is the globular grease or oil cup or receptacle 14, which is held from displacement later- 85 ally in three directions by the standards 10. 85 However, the grease cup is held from dis- placement in a fourth direction by the head of the split pin 15, which extends through the plate 8.

To secure the U-shaped member 4 to the 90 arm 2, a thumb bolt 16 is provided, which is threaded through one of the arms 3. The arms 3 engage upon each side of the guide rail or track of the elevator shaft, thus constituting means for guiding the lubricator 95 device relatively with regard to the track.

The plate 8 is provided with a shouldered portion 17. Wick holders 19 are provided which are constructed of sheet brass or any other suitable material. These holders are 100 slightly elliptical in cross section and are designed to receive the end portions of the U-shaped wick 20, the loop 21 of this wick resting upon the top of the plate 8, and is of sufficient width to permit of adjustment of 105 the holders. To adjust the holders, the same are provided with extensions 22, which are supplied with down-turned flanges 23, which engage the shouldered portion 17, thus constituting guiding means for the holders. To 110 hold the down-turned flanges of the exten- sions adjacent the shouldered portion 17,

washers 23^a are provided, through which the screw bolts 24 extend so as to hold them in place, there being nuts 25 threaded upon the screw bolts 24. The U-shaped wick 20 feeds 5 the lubricant or grease to the wicks 26, which are secured in the holders by the split pins 27. Suspended at the lower ends of the wicks 26 are the gravitating members 28. These gravitating members 28 are designed 10 to distribute the grease or lubricant proportionately upon the faces of the guide track or rail of the elevator shaft.

A central wick 29 is secured to the shoul- 15 dered portion 17 of the plate 8, with its end 30 extended through a slot of the plate 8 and arranged in the globular grease or oil cup. A split pin 31 is utilized for securing the central wick in place. A gravitating mem- 20 ber 32, like the gravitating members 28, is suspended from the central wick, and dis- 25 posed adjacent the outer face of the guide rail or track of the elevator shaft. Thus it will be observed that by virtue of the gravi- 30 tating members 28 and 32, three faces of each guide rail or track are thoroughly 35 greased or lubricated.

The gravitating or compression members 28 and 32 are similarly constructed, namely, they comprise the bent plates 33, between 30 which the extremities of the wicks 20 and 29 and extra pieces of wick material 34 are clamped. Also clamped in between the plates and in the wick material are metallic 35 members 35, thus constituting means for ob- 40 viating to a great extent the wear upon the wick material. The plates 33 are provided with lugs 36 adapted to be inserted through the apertures 37 of the fiber disks 38, and afterward clenched or bent in opposite di- 45 rections, as shown in the drawings. These fiber disks constitute flanges or means, be- 50 tween which the rail or guide track of the elevator shaft passes.

The wick 29 rests upon the loop of the 45 wick 20, so that as the grease or oil feeds up the wick 29, it is transferred therefrom to the wick 20. The grease or lubricant feeds along the ends of the U-shaped wick 20 to the wicks 26, and down to their ex- 50 tremities, beyond the plates 33, from which it is supplied upon the faces of the guide rails or tracks of the elevator shaft.

The gravitating members 28 not only con- 55 stitute means for holding the wicks adjacent the guide rails or tracks of the elevator shaft, but also constitute means for retard- 60 ing the feed of the lubricant through the wick. For instance, when constructing the gravitating members, the wicks 26 and the extra pieces of wick material 34 when placed together are substantially twice as thick as the diameter of the apertures 37, thus neces- 65 sitating sufficient pressure upon the plates 33, so as to compact the wicks and the extra pieces 34 closely together, so that the lugs 36

will pass through the apertures 37. By com- 70 pressing the wicks 26 and the extra pieces of material 34 together the lubricant containing cells of the fabric will be consider- ably closed, thus retarding the lubricant as it feeds.

The invention having been set forth, what is claimed as new and useful is:—

1. In combination, a frame adapted to be secured to an arm of an elevator cage, a 75 pair of wick holders carried by the frame including feeding wicks, means for permitting two of the wick holders to be adjusted toward and away from one another, and means constituting compression devices sus- 80 pended from the free ends of the wicks to retard the lubricant.

2. In combination, a frame, a grease cup carried thereby, a pair of wick holders adjustably carried by the frame including 85 wicks, a central wick overlapping the first wicks and extending into the grease cup, and members constituting compression devices suspended from the free ends of the wicks to retard the lubricant.

3. In a device as set forth, a frame having a plate provided with a shoulder, a pair of wick holders having means to engage the shoulder movable longitudinally thereof, de- 95 vices carried by the plate for engaging said means for holding the wick holders in ad- justed positions.

4. In a device as set forth, a frame having a plate provided with a shoulder, a pair of wick holders having means to engage the 100 shoulder, devices carried by the plate for en- gaging said means for holding the wick holders in adjusted positions, a U-shaped wick carried by the holders, a grease cup, a wick disposed centrally of the loop of the 105 U-shaped wick for transferring the grease or lubricant from the cup to the U-shaped wick, said cup being suspended below the plate into which the central wick extends, and gravitating members carried by the ex- 110 tremities of the U-shaped wick and the central wick.

5. In a device as set forth, a grease or lubricant feeding wick, a gravitating mem- 115 ber suspended therefrom constituting a lubricant retarding device, said member comprising two bent plates between which the wick is clamped, and means for clamp- ing the plates together.

6. In a device as set forth, a compression member, suspended from the extremity of a fabric wick, said member comprising a pair of bent plates, a wick secured therebetween, and means for clamping the plates with the wick between them together, and means em- bedded in the wick to obviate wear thereon.

7. In a device as set forth, a frame having a grease cup, fabric wicks having a portion of one wick extending into the cup and lying over a portion of the other wick, and means 130

for holding the wicks, said holding means including means to permit of adjustment thereof, and gravitating members suspended from the fabric wicks.

5 8. In combination, a frame having a grease cup, fabric wicks having a portion of one wick extending into the cup and lying over a portion of the other wick, holding means for the wicks, and gravitating lubricant 10 retarding members suspended from the free ends of the fabric wicks.

9. In a lubricator for elevator tracks, a plurality of weighted wicks adapted to engage the edge and sides of said track, said 15 wicks being gravity-actuated.

10. In a lubricator for elevator tracks, a plurality of feeding devices adapted to engage said track, said feeding devices including wicks, each wick having rigid members, 20 adapted to resist the wear thereon.

11. In a lubricator for elevator tracks, a feeding wick, plates disposed on each side of said wick, said plates having reduced portions, apertured disks adapted to engage said

reduced portions, for holding said disks in 25 position.

12. In a lubricator for elevator tracks, suspended wicks adapted to engage each side of said track, said wicks being gravity actuated, and slid able means for permitting 30 said wicks to be moved inwardly or outwardly.

13. A lubricator for elevator tracks including a plurality of suspended fabric members, having means at their ends for compressing the same to retard the lubricant. 35

14. A lubricator for elevator tracks including suspended fabric lubricant feeding members, having compression means at their free ends to retard the lubricant. 40

In testimony whereof I have signed my name to this specification in the presence of two subscribing witnesses.
